UNITED STATES PATENT OFFICE

116,633

DESIGN FOR A TINSEL APPLIQUÉD FABRIC

Gustave Rubner, Tuckahoe, N. Y.

Application February 17, 1939, Serial No. 83,065

Term of patent 3½ years

To all whom it may concern:

Be it known that I, Gustave Rubner, a citizen of the United States, residing at Tuckahoe, county of Westchester and State of New York, have invented a new, original, and ornamental Design for a Tinsel Appliquéd Fabric, of which the following is a specification, reference being had to the accompanying drawing, forming part thereof, wherein—

The figure is a plan view of a tinsel appliquéd fabric, showing my new design.

I claim:

The ornamental design for a tinsel appliquéd fabric substantially as shown.

GUSTAVE RUBNER.
